UNITED STATES PATENT OFFICE.

CONRAD JURKOVICH, OF OTTAWA, ILLINOIS.

NON-REFILLABLE BOTTLE.

1,175,269.

Specification of Letters Patent. Patented Mar. 14, 1916.

Application filed September 8, 1914. Serial No. 860,755.

To all whom it may concern:

Be it known that I, CONRAD JURKOVICH, a subject of the King of Hungary, residing at Ottawa, in the county of La Salle and State of Illinois, have invented certain new and useful Improvements in Non-Refillable Bottles, of which the following is a specification, reference being had therein to the accompanying drawing.

This invention relates to non-refillable bottles and has for its object to provide a bottle of such class, in a manner as herein-after set forth, with means to enable the contents of the bottle to be discharged and to prevent the partial or complete refilling of a bottle.

Further objects of the invention are to provide a non-refillable bottle which is simple in its construction and arrangement, strong, durable, efficient and convenient in its use, readily set up and comparatively inexpensive to manufacture.

With the foregoing and other objects in view the invention consists of a novel construction, combination and arrangement of parts as hereinafter more specifically described and illustrated in the accompanying drawings wherein is shown an embodiment of the invention, but it is to be understood that changes, variations and modifications can be resorted to which come within the scope of the claim hereunto appended.

In the drawings wherein like reference characters denote corresponding parts throughout the several views, Figure 1 is a vertical sectional view of a bottle, broken away, showing the formation of a bottle neck of a non-refillable bottle in accordance with this invention. Fig. 2 is a vertical sectional view, broken away, of a non-refillable bottle in accordance with this invention. Fig. 3 is a top plan view of a valvular element employed closing the neck. Fig. 4 is a vertical sectional view of a valvular element. Fig. 5 is a plan view of the lower end of the valvular element.

Referring to the drawings in detail 6 denotes a body portion of a bottle and 7 the neck in which is formed a throat 8. The wall 9 of the throat 8, is formed with an annular flange 10 intermediate the ends of the throat. The said flange 10 is adapted to suspend within the throat a valvular element to prevent the partial refilling or com-

plete refilling of the body portion 6 of the 55 bottle. The valvular element includes a hollow annular member 11 which decreases in diameter from its lower toward its upper end and is formed at its lower end with an inwardly extending annular flange 12, 60 which constitutes a seat for a pair of flap valves 13, 14, which are pivoted upon a pin 16, carried at the lower end of the member 14.

The member 11 at its top is provided with 65 a cap piece 17, which is formed with a pair of annular shoulders 18, 19, one arranged above the other.

Secured to the periphery of the member 11, is a pair of holding springs 20, having 70 their upper ends provided with inwardly projecting extensions 21. The springs 20 are curved in the direction of their length. When the valvular element is positioned in the throat 8 of the bottle neck 7, the shoulder 19 is seated upon the flange 10, and the shoulder 18, is flush with the lower face of the flange 10. The projections 21 of the springs 20 bear against the lower face of the flange 10, and also against the shoulder 80 18. Under such conditions the valvular element is maintained in position, that is to say, it is prevented from being forced inwardly, and from being pulled outwardly.

The cap piece 17 is provided throughout 85 with openings 22 to permit of the discharge of the contents of the bottle, when the valves 17, 14 are shifted off their seats, when the bottle is tilted for the purpose of pouring contents therefrom.

What I claim is:—

The combination with a bottle neck formed with an annular flange in the throat thereof, of a valve consisting of a perforated cap member adapted to seat upon said flange, a circumferential flange formed integral with one face of said cap and co-extensive in circumference and thickness with the inner edge of said flange, an annular depending member formed integral 100 with said circumferential flange near the inner face thereof, an inwardly extending annular flange formed integral with the lower end of said annular depending member, a bearing interposed transversely of 105 said last-mentioned flange, oppositely disposed semi-circular valve plates pivoted upon said bearing, and retaining springs

secured at their lower ends upon the lower portion of said depending member and formed with inward extensions on the upper ends engaging the bottom face of said circumferential flange, and adapted to engage the bottom face of said first mentioned flange when in operative position.

In testimony whereof I affix my signature, in the presence of two witnesses.

CONRAD JURKOVICH.
